UNITED STATES PATENT OFFICE

2,014,601

ROTARY PUMP

Francis Wheatley, Sr., Kansas City, Mo.

Application July 30, 1932, Serial No. 626,542

1 Claim. (Cl. 103—123)

My invention relates to rotary pumps and one object is to provide a pump of this character in which the impeller is so constructed as to have powerful suction qualities whereby it is enabled 5 to economically pump oil, water or other liquids from deep wells or other sources.

A further object is to provide a rotary pump in which the working parts are automatically controlled so that very little if any attention is 10 required on the part of an attendant.

Other objects will hereinafter appear, and in order that the invention may be fully understood reference will now be had to the accompanying drawings, in which:

15 Fig. 1 is a front elevation of the pump.

Fig. 2 is an irregular vertical section on line 2—2 of Fig. 1.

Fig. 3 is a central vertical cross section of the pump.

20 Fig. 4 is a detail front elevation of one of the Y-couplings or manifolds employed in carrying out the invention.

Fig. 5 is a detail perspective view of a packing ring.

25 Fig. 6 is a broken horizontal section of a pair of valves on line 6—6 of Fig. 3.

Referring in detail to the different parts, 2 designates the cylinder of the pump which consists of two sections 4 and 6 having parallel side 30 walls and secured together at their abutting portions with suitable means such as bolts 8 and provided at their lower portions with outturned base members 10 and 12 bolted or otherwise firmly secured to a bed plate 14.

35 16 designates a rotary impeller which operates in an annular chamber 18 formed within the sections 4 and 6 of the cylinder 2. The impeller 16 is provided near each end with a split packing ring 20 fitting snugly within the chamber 18 to enhance the suction quality of said impeller so 40 that it may economically draw oil, water, or other liquids from deep wells or other sources.

The impeller 16 is fixedly mounted upon a 45 radial arm 22 projecting from a hub 24 fixedly mounted upon a drive shaft 26 journaled in a plurality of bearings 28 secured upon the bed plate 14. The shaft 26 is prevented from shifting longitudinally within the bearings 28 by a pair of collars 30 fixedly mounted upon said shaft 26 and arranged adjacent to the intermediate bearings 28, Fig. 1. The shaft 26 is equipped with a fixedly mounted gear wheel 31 which may be driven from any suitable source (not shown) as a steam engine, electric motor, or the like.

55 The arm 22 extends through an annular slot

32 formed between the two cylinder sections 4 and 6. Said slot 32 is closed by a split packing ring 34 provided near its ends with transverse notches 36 into which the rings 20 project and thereby cause said packing ring 34 to rotate with the impeller 16. The packing ring 34 travels upon annular shoulders 37 forming the sides of the slot 32 and prevents leakage of liquid through said annular slot and out to atmosphere through a circular opening 38 formed in the central portion of the cylinder 2. The packing ring 34 is prevented from being forced too tightly into frictional contact with the shoulders 37 by suitable means such as a plurality of set screws 40 threaded in a split ring 42 which is spaced from but arranged concentrically within the packing ring 34, Figs. 2 and 3.

5 After being properly adjusted the set screws 40 are firmly secured by lock-nuts 44 which are adjusted into engagement with the inner periphery 20 of the split ring 42, the ends of which latter abut opposite sides of the arm 22 in order to rotate therewith. The packing ring 34 is provided with a plurality of small transverse openings 46 through which liquid entering the chamber 18 25 may pass and lubricate the contacting surfaces of said packing ring 34 and the shoulders 37.

Liquid is sucked by the impeller 16 into the annular chamber 18 through inlet ports 48, formed in the lower portion of the cylinder sections 4 and 6, and is forced by said impeller through outlet ports 50 formed in the lower portion of the cylinder sections 4 and 6. The inlet ports 48 communicate with a Y-coupling, or manifold 52 connected to an inlet pipe 54 which extends into the well or other source from which the liquid is being pumped. The outlet ports 50 communicate with a Y-coupling 56 connected to a discharge pipe 58 which conducts the liquid to any desired point. As shown by Figs. 1 and 4 the coupling 56 has two oppositely disposed parallel flanges adapted to fit against and be firmly secured to the parallel side walls of the cylinder 2.

In order to cause the liquid to flow through the annular chamber 18 and out through the outlet ports 50 a pair of valves 60 and 62 are interposed between the inlet and outlet ports 48 and 50, respectively. As more clearly shown by Fig. 3, the valves 60 and 62 are reciprocably mounted in housings 64 and 66 which are preferably formed integral with the lower portion of the cylinder sections 4 and 6 and provided with removable caps 68 and 70 equipped with leak-proof stuffing-boxes 72 and 74 through which stems 76 and 78 of the valves 60 and 62, respectively, pro-

ject. The adjacent ends of the valves 60 and 62 are arranged to overlap when closed, as shown by Fig. 6, and thus form a leak-proof joint and their upper adjacent portions are recessed as indicated at 80 to snugly fit against the packing ring 34 and form a leak-proof joint.

Leakage of liquid around the upper and lower edges of the valves 60 and 62 is prevented by packing elements 82 and 84 forced against the adjacent surfaces of the housings 64 and 66 by springs 86 and 88, respectively, which latter also force the valves 60 and 62 against the upper portion of the respective housings 64 and 66.

As a further precaution against leakage of liquid around the valves 60 and 62 the side of said valves nearest the inlet ports 48 are pressed against the adjacent sides of the housings 64 and 66 by means of springs 90 and 100, which also press packing elements 102 and 104 against the opposite sides of the housings 64 and 66, respectively.

The outer portions of the valve stems 76 and 78 are reciprocably mounted in slideways 106 and 108 mounted upon the bed plate 14. Said stems 76 and 78 are reciprocated by means of cams 114 and 116 and antifriction rollers 118 and 120, which latter are mounted upon spindles 122 and 124 secured to the valve stems 76 and 78, respectively. The rollers 118 and 120 extend into peripheral grooves 130 and 132 formed in the respective cams 114 and 116. Said grooves 130 and 132 have lateral extensions 134 and 136 which upon engaging the rollers 118 and 120 force the latter to open the valves 60 and 62 through the intermediary of the stems 76 and 78 to permit the impeller 20 to pass, after which they immediately

close said valves, so that liquid drawn into the chamber 18 by the impeller will be forced through the outlet ports 50.

With the foregoing arrangement it is apparent that the operation of the pump is attended with but little friction and a steady stream of liquid is forced from the pump during the operation of the impeller 20.

From the foregoing description it is apparent that I have provided a rotary pump embodying the advantages above pointed out, and while I have shown one form of the invention, I reserve all rights to such changes and modifications as properly fall within the spirit and scope of the invention as claimed.

Having thus described my invention, what I claim and desire to secure by Letters Patent, is:

A rotary pump comprising a cylinder with parallel side walls having inlet ports at its opposite sides and outlet ports at its opposite sides and close to said inlet ports, a one piece Y-shaped manifold straddling the cylinder and communicating with said inlet ports, a Y-shaped manifold straddling the cylinder and communicating with the outlet ports, parallel flanges on said manifold adapted to fit snugly against and be firmly secured to the parallel side walls of the cylinder, a rotary impeller operably mounted within said cylinder, reciprocatory valves extending transversely through the cylinder and located between the inlet and outlet ports, and means for opening the valves to allow the impeller to pass and to close said valves after passage of said impeller.

FRANCIS WHEATLEY, SR.
